UNITED STATES PATENT OFFICE.

GEORGE HAVELL, OF NEWARK, NEW JERSEY.

BUTTON-HOOK.

SPECIFICATION forming part of Letters Patent No. 289,095, dated November 27, 1883.

Application filed August 15, 1883. (No model.)

To all whom it may concern:

Be it known that I, GEORGE HAVELL, a citizen of the United States, residing in the city of Newark, county of Essex, and State of New Jersey, have invented certain new and useful Improvements in Hinged Button-Hooks, fully described and represented in the following specification and the accompanying drawings, forming a part of the same.

10 This invention relates to that class of button-hooks hinged, like a knife-blade, in a handle; and it consists in the specific construction of the handle and spring, as herein described, and the combination of the same with one 15 another and with the pivoted button-hook. The nature of my construction will be fully understood from the description and drawings attached hereto.

20 In the drawings annexed, Figure 1 is a side view of the entire tool, with one side of the handle cut away to exhibit the arrangement and operation of the spring. Fig. 2 is a view of the blank for the handle, as constructed of sheet metal, and provided with a hole for 25 the insertion of the fixed end of the spring. Fig. 3 is a view of the spring detached from the handle; and Fig. 4 is an edge view of the back of the tool, showing the end of the spring inserted in its working position.

30 A is the handle, formed of sheet metal from a blank, A', and constructed with holes a a, for the hinge-rivet, and a hole, b, for retaining the spring in place, the latter hole being formed in the center of the back, near the end 35 opposite the hinge.

B is the hook, formed of any desirable shape, and hinged to the handle by a rivet, c, like a blade in a knife, the butt of the hook being suitably formed to press upon the spring, 40 as in similar constructions.

C is the spring, formed of hard spring-wire, and constructed to press at one end against the butt of the hook, while the other end is bent to bear against the inside of the handle 45 and project through the hole b in its back. The spring is formed with a bend or projection, d, near its rear end, to form a fulcrum, the point where it presses inside the handle being indicated at e in Fig. 1. The end where 50 it is passed through the hole in the handle is also made with a short offset, o, to lock it into the hole b, the construction requiring that the rear end of the spring should be inserted in the hole b endwise, which can only be done before the hook is riveted in. The securing

of the hook thus locks the offset o in the hole b and brings the fulcrum d into close contact with the inside of the handle at e, thus developing the pressure of the spring upon the butt of the hook as desired.

It is obvious that the end o, which part of the spring is inserted in the hole b, might be riveted upon the outer side of the handle, if desired; but such an additional fastening adds nothing to the operation of the spring and increases the cost of construction.

I am aware that a sheet-metal handle similar to that I employ is not new, as the same has been used heretofore with a different spring, and with special features adapted to 70 the spring employed, as in United States Patent No. 240,749, of April 26, 1881. I do not, therefore, claim a sheet-metal handle and spring, except as described herein. My invention differs from that referred to in not 75 requiring a shouldered recess at one end to retain the spring in place; in not requiring any open slot at the pivot end to clear the free end of the spring, and in requiring nothing but a bit of bent wire for the spring. 80 The dies used for making the blanks for my handles are thus much cheaper to construct and less liable to damage in use than if constructed to produce a shouldered recess in the blank. The only preparation my blank requires to retain the spring in place is the punching of the small hole b, which is of the simplest form known; and the shape required for the spring is also instantaneously imparted to the piece of wire used by striking 85 it up in a die in the ordinary mode common for such bent articles.

Having fully set forth the shape of the spring and the construction required in the handle to operate with it, I claim the same, as 90 follows:

The hinged button-hook herein shown and described, and constructed with the sheet-metal handle A, formed with the hole b near the butt-end, and the wire spring C, shaped 100 as described, and secured in the hole by the offset o, all substantially as set forth.

In testimony whereof I have hereunto set my hand in the presence of two subscribing witnesses.

GEORGE HAVELL.
